FIG. 1

FIG. 2

FIGURE 1 is a perspective view of a bowling shoe or similar article of this invention.

FIGURE 2 is a plan view of the bowling shoe or similar article of FIGURE 1.

The characteristic feature of my design resides in the combination on a bowling shoe of the type disclosed of a series of arbitrary symbols or marks extending upwardly from the sole, so that three marks are spaced to the front and three to the back, substantially as shown in full lines.

I claim:

The ornamental design for a bowling shoe or similar article, substantially as shown and described.
